SHEET MATERIAL HANDLING

Howard W. Daves, Alcoa, Tenn., assignor to Aluminum Company of America, Pittsburgh, Pa., a corporation of Pennsylvania

Application April 4, 1946, Serial No. 659,563

9 Claims. (Cl. 271—74)

1

The hereinafter described invention relates generally to material handling mechanisms, and while not necessarily so limited in its adaption, relates more particularly to mechanism for receiving strips, sheets or plates of material such as metal, or the like, in successive order and thereafter automatically stacking or piling the same in an orderly fashion.

It is a principal object of the invention to provide mechanism of the general character above indicated which readily adapts itself to association with types of machinery, such as flying shears, rolling mills, sheet and strip processing devices and semi- or wholly automatic equipment whose output will be greatly enhanced by the mechanism of the invention.

A further object of the invention is to provide a mechanism that is adjustable to varying sizes and types of material requiring handling and stacking.

Another object is to supply a sheet handling and stacking apparatus that is automatically controlled in its operation by the material presented and passing through the same.

A further object is to provide a mechanism which is capable of receiving, conveying and thereafter discharging material, preferably in sheet or plate form, in orderly stacked relationship with a minimum amount of surface interference or contact with mechanical engaging means during the handling of successive sheets of material.

These and other objects will become apparent to those versed in the art on consideration of the detailed description of the invention as described in connection with one embodiment thereof and illustrated in the appended drawings, in which:

Fig. 1 represents a top plan view of a sheet handling and stacking mechanism in association with a delivery or charging device;

Fig. 2 represents a side elevation of the mechanism illustrated in Fig. 1 with parts broken away to more clearly show the incorporated construction;

Fig. 3 represents an end elevational view of the mechanism taken in the direction of the arrows III—III on Fig. 2; and

Fig. 4 represents a sectional, elevational view taken along the line IV—IV of Fig. 2.

Referring now to the drawings, in which like reference numerals designate corresponding parts and elements throughout the several views, the mechanism of this invention has been illustrated as incorporating a material delivering or charging unit, a receiving and conveying unit, an auto-

2

matically functioning fluid pressure applying and material guiding means, and a stack receiving apparatus, each of which is represented in its individual entirety by the reference numerals 10, 50, 90 and 110, respectively.

Referring to the material delivering unit 10, this unit is constructed in the form of a main frame comprising side members 12, 14, preferably in the form of structural channels. The side members are tied together in rigid structural relationship by cross members 15, 16 and 17 to form a rigid frame structure for supporting horizontally disposed belt pulleys or drums 18, 19, 28 and 21. The aforementioned belt pulleys or drums, in cooperation with belt tightening pulleys 22, support a plurality of endless belts 24, the top surfaces of which serve as a conveyor to transport material brought into contact therewith, the translatory motion imparted to the material being one of delivery in the direction of the arrow (Fig. 2).

In order that the endless belts 24 may be maintained at a uniform tension, the belt tightening pulleys 22 are each rotatably supported in suitable individual frames 28, pivotally mounted on shaft 30, the latter being supported in bearings 31 that are mounted on brackets 32 secured to side members 12 and 14. The belt tightening frames 28 are each constructed in the general form of a bell crank and carry dead weights 34 of sufficient magnitude to tend to rotate frames 28 in an anti-clockwise direction to exert uniform tension in each of the belts 24 through the action of belt tightening pulleys 22 supported therein.

In order that belt pulleys 18, 20 and 21 may be suitably aligned and adjusted with respect to idler pulley 19 and the axis of frame 10, the various shafts supporting these pulleys have been mounted in suitable bearings 35, 36 and 37, respectively, that may be shim adjusted through the medium of suitable shim stock with respect to the main frame 10. In a similar manner, bearings 31, supporting the belt tightening frames 28, are shim mounted to permit alignment and adjustment of shaft 30 with respect to the remaining endless belt pulleys and frame 10.

The actual delivery unit 10 hereinabove described may be employed as a runout table, receiving conveyor or other material handling device normally disposed at the discharge side of a material processing or fabricating apparatus, such as a rolling mill, flying shear, printing press, or the like, its chief purpose in conjunction with the present invention being to provide a delivery

or charging means for material presented thereto.

To the left of delivery unit 10 and in cooperation therewith, as illustrated in Figs. 1 and 2, is a receiving and conveying unit 50. This unit comprises a main frame supported by four leg members 52 which are tied together at their upper ends by means of cross beams 54. Adjacent the cross beam members 54 and immediately below the same, two cross shafts 55 and 56 are supported in suitable bearings 58 secured to the outer surfaces of members 52.

A belt supporting frame, represented in its entirety by the reference numeral 60, is secured to the underside of cross beams 54 and ties them together longitudinally. This belt supporting frame is preferably constructed from two side rails in the form of structural channel members 61 provided with bearing members 62 (Fig. 4) for receiving the aforementioned shafts 55 and 56.

The rail members 61 are further tied together at suitably spaced intervals along their length by means of cross members 64 which preferably take the form of structural angle members. Cross shafts 65 are disposed at each end of frame members 61 and are supported in bearings 66 carried by these rail members. In the preferred construction of the apparatus of the invention, bearings 66 are shim mounted with respect to rails 61 in order that shafts 65, supported therein, may be properly aligned and adjusted with respect to the axis of main frame 50. The shafts 65, in each case, support belt pulleys or drums 67 which carry or support a plurality of endless belts 69, the upper runs of the belts passing over an intermediate idler roller or drum 68, supported intermediate the ends of frame 60, and a belt direction changing pulley or drum 40. The drum 40 is preferably supported on shaft 42, carried in bearings 43, which are adjustably mounted on rail members 61 adjacent the right end drum, or pulley 67, as viewed in Fig. 2. Suitable bell crank type belt tighteners 70, incorporating belt tightening pulleys 71, are pivotally supported at 72 upon frame 60 for the purpose of maintaining a definite tension on endless belts 69 through counterclockwise movement under the influence of dead weights 73.

Belt backup means, in the form of wood boards 80, is secured to the underside of frame 60, the disposition of these boards being such that they lie with the lower surface thereof in a plane tangential to the underside of belt drums 67, as best seen in Figs. 2 and 4.

An automatically functioning fluid pressure applying means 90, in combination with sheet or edge guiding members, is dependently supported from cross shafts 55 and 56. The guide portion of this assembly comprises rail members 92 provided with internally threaded nut members 93 secured thereto (Figs. 3 and 4), the nut members being threadingly engaged with right and left hand threaded portions of shafts 55 and 56, the purpose of which will be herein-after more fully described. For ease in construction, the shafts 55 and 56 have been made in two sections coupled by means of a sleeve 57, as best shown in Fig. 4.

Depending fingers 95 are secured to rails 92, the inner vertical faces of the rails and fingers being flush with each other. Distributor pipes 98 are, in turn, secured to the depending fingers 95, as by means of suitable clamps 99, these pipes being set back from the inner vertical surfaces

of the depending fingers and below the lower edges of the contiguous rails 92 (Fig. 4) so as to provide a vertical, unobstructed area between the oppositely disposed sets of guide rails and fingers. Each distributor pipe 98 is provided along its length with spaced nozzles 100, the angle of discharge of the nozzles being directed inwardly and upwardly, as best disclosed in Fig. 4.

The otherwise open ends of distributor pipes 10 or manifolds 98 are suitably sealed or capped, and fluid pressure connection is made with the interior of the distributor pipes from a header pipe or manifold 102 through the medium of flexible hose members 104.

In order that the mechanism of the invention may be adapted to the handling of various widths of material, a means has been provided for adjusting the lateral distance between guide rails 92. This means comprises the aforementioned shafts 55, 56 in cooperation with the internally threaded nut members 93. Sprockets 105 and 106 are secured to an outboard end of shafts 55 and 56, respectively, and an endless roller chain is engaged with said sprockets for the purpose of mechanically interconnecting the same. A hand wheel 108 is secured to the opposite end of shaft 56. Rotation of this hand wheel serves to impart rotation to shafts 55 and 56 simultaneously thereby separating or closing the depending guide members 92, together with their fixed associated elements, through the action of internally threaded nut members 93 and right and left hand threaded portions of shafts 55 and 56.

A material receiving platform 110 is located beneath the material receiving and conveying unit 50. The platform 110 may be any suitable type capable of being removed or replaced as desired by means of well known industrial type tractor devices. Its chief object is to receive material disposed thereon in an orderly stacked fashion, as will be hereinafter more fully described. In lieu of the platform 110, other forms of mechanism may be employed, such as a roller table of the power or gravity type, or a material receiving mechanism of the car type movable on tracks, all of which material handling mechanisms being well known.

The power drive for the mechanisms of this invention may be supplied direct from the mechanism with which it is associated. A relatively simple form of drive incorporates chain-connected sprockets 112, 114 (Fig. 1), which drive coordinates movement of endless belts 24 and 69. The shaft supporting gear 112 may be driven by the same prime mover driving the mechanism with which delivery unit 10 is associated. In this manner, the endless belts 24 and 69 will be driven in proper timed relationship with respect to the particular material processing apparatus with which the mechanisms of this invention have been associated.

The delivery unit 10 and the receiver and conveyor unit 50 are disposed in serial relationship with their endless belts 24, 69 in overlapping relationship, as shown in Figs. 1 and 2, the material being delivered to the underside of belts 69 by belts 24. It will be understood that the longitudinal center line of the receiving unit 50 is in alignment with the center line of travel of the material as it is presented thereto from the mechanism with which delivery unit 10 is associated. It will also be understood that units 10 and 50 may be associated in such a manner that belts 69 overlap belts 24 an appreciable distance

to insure and facilitate entrance of material being handled by the mechanisms of this invention.

In operation, sheet or like material delivered to belts 24 is charged or conveyed forwardly from right to left, as viewed in Fig. 2 of the drawings. Progress of the material along belts 24 intercepts a beam of light emanating from a light source 116, absence of which reacts with photoelectric cell 118, relay 119 and solenoid valve 120 to admit fluid pressure, such as air under pressure, to header 102. From the header 102, air pressure is delivered to distributor pipes 98 and escapes through nozzles 100 in a direction to impinge upon the underside of sheet 122 (Fig. 4). The air pressure is so selected in terms of the weight of the material being handled to float the same in surface contact with the underside of belts 89 during translation of the sheet by these belts. Passage of the end of a sheet of material to the left beyond light source 116 causes the light beam, in cooperation with the photo-electric cell 118, relay 119 and solenoid valve 120, to close the valve 120 and thereby shut off air pressure at nozzles 100. Termination of air flow from nozzles 100 permits a sheet of material previously supported thereby to gravitationally fall upon platform 110, or upon the uppermost sheet thereon.

It will be appreciated that some time delay will be required in the actual closure of solenoid valve 120 to cut off air flow in order to allow the sheet to be moved to a key discharge point so as to thereby insure regular and orderly stacking of material by the mechanism of this invention. In this connection, it has been found that a delay of about 2½ seconds in the closure of solenoid valve 120, after the end of a sheet passes the light beam emanating from source 116, is successful in controlling air pressure or flow in the handling of 42" width sheet material weighing 9½ pounds per lineal foot, where the air jets are spaced on 6" centers along the length of distributor pipes 98. Since the fluid pressure and interval of operation of the solenoid valve are both adjustable in their operation, various combinations of air pressure and valve operation may be selected to suit a particular material being handled by the mechanism of this invention. For example, the interval of non-operation of fluid pressure may be obtained by utilizing any of the well known forms of circuit timing devices in the control circuit of solenoid valve 120. The same applies to the relative position of guide rails 92, these members being adjustable to suit the particular width of material it may handle. Distributor pipes 98 move with, and are thereby adjusted with, any adjustment made to guide rails 92, which insures correct directional application of fluid pressure upon the material being handled.

Although the invention has been described in connection with a specific form of apparatus, it is to be understood that it is not thereby limited in any way, except as defined in the appended claims, in which:

1. In a material handling mechanism, a material receiving and conveying means, fluid pressure distributing means disposed beneath and longitudinally of said first-mentioned means and directed upwardly towards a sheet of material in contact with the first-mentioned means, and means including a valve responsive to said material disposed between a source of fluid pressure and the distributing means for terminating the fluid pressure to permit gravitational release of said sheet.

2. Stacking apparatus comprising in combination, a framework, an endless belt carried thereby, means for feeding successive sheets to be stacked to the underside of said belt, means disposed beneath and longitudinally of said endless belt for directing jets of air upwardly against the underside of each sheet to hold the same in floating contact with said belt, and a valve member actuated by each sheet to cut off said air jets to gravitationally release the sheet.

3. A material handling system comprising a belt conveyor means for receiving and conveying material, a delivery mechanism for delivering said material in successive sheets to said belt conveyor means, said delivery means being disposed adjacent and below one end of said conveyor means, fluid pressure exerting means below and longitudinally of said conveyor means and directing fluid pressure upon the under surface of a sheet of material delivered to the conveyor means by the delivery means, said fluid pressure serving to maintain a sheet of material in contact with the belt conveyor means, a valve member admitting fluid pressure to said pressure exerting means, said valve member being actuated by the trailing edge of a sheet of material to terminate the fluid pressure, whereby successive sheets of material gravitationally fall into stacked relationship below said conveyor means.

4. In a material handling system, a material delivery means comprising a frame supporting a plurality of endless belts, individual belt tighteners associated with each belt to maintain uniform tension in all of said belts, a material receiving means comprising a frame supporting a plurality of endless belts, individual belt tighteners associated with each of the latter belts to maintain uniform tension therein, means for coordinating movement of said two systems of endless belts in timed relationship, fluid pressure means disposed below and longitudinally of the endless belts of the receiving means to floatingly hold material in contact with the underside of the endless belts during movement from the delivery to the receiving means, and automatic cut-off means responsive to said material for terminating the fluid pressure when the material has progressed beyond the delivery means.

5. In combination, a sheet receiving device, an endless conveyor extending rearwardly therefrom and disposed in position for receiving successive sheets adjacent the underside thereof, a rail member disposed at each side of said conveyor beneath the same and longitudinally thereof, each rail having a vertical depending surface for limiting lateral movement of sheets traveling therebetween, a longitudinal manifold carried by each rail member and having a series of spaced orifices in line for discharge of air under pressure in a direction extending inwardly and upwardly with respect to said vertical surface, whereby to hold the sheet against the underside of said conveyor, and a valve responsive to each sheet for terminating discharge of air from both of said manifolds.

6. A material handling mechanism comprising a conveyor system, a fluid pressure distributing system directing pressure towards said conveyor system over substantially its entire length to maintain a sheet of material in floating contact with said conveyor system, a source of fluid pressure in communication with the fluid pressure distributing system, a valve member associated with the source of fluid pressure and distributing system, said valve member having manipulating

means disposed in a path of movement of the sheet of material and responsive thereto to cut off fluid pressure in the absence of a sheet of material.

7. In a material handling mechanism, a continuously running conveyor, an intermittently operating fluid pressure distributing system below and longitudinally of said conveyor and directing fluid pressure against the underside of a sheet of material delivered to said conveyor to maintain the same in floating contact therewith, a valve controlling fluid pressure to said pressure distributing system, said valve having manipulating means disposed in the path of movement of the sheet of material and responsive thereto to cut off fluid pressure in the absence of delivery of a sheet of material to the conveyor.

8. A sheet material handling and stacking mechanism comprising a delivery means, a conveyor means and a stack receiving means, a fluid pressure distributing system below and longitudinally disposed in respect to said conveyor means and located above said stack receiving means, a source of fluid pressure in communication with said distributing system, a valve mechanism between said source of fluid pressure and distributing system, and a valve actuating member for controlling fluid pressure at the distributing system, said valve actuating member having a manipulating means disposed in the path of movement of sheet material delivered to the conveyor means and responsive thereto to deliver fluid pressure to the fluid distributing system to maintain a sheet of material in surface contact with the conveyor means, and passage of said sheet of material beyond said valve actuating manipulating means cutting off said fluid pressure at the distributing system to permit gravitational stacking of the sheet of material on said stack receiving means.

9. A sheet material handling and stacking mechanism comprising a delivery means, a conveyor means and a stack receiving means, a fluid pressure distributing system below and longitudi-

nally disposed in respect to the conveyor means and located above said stack receiving means, a source of fluid pressure in communication with said distributing system, a valve mechanism between said source of fluid pressure and distributing system, said valve mechanism including a beam of light disposed above the path of travel of a sheet of material delivered to the conveyor and directed towards a light sensitive cell in the valve mechanism, said beam of light intercepting by a sheet of material maintaining fluid pressure at the distributing system to float the sheet of material into surface contact with the conveyor means, and said beam of light reacting on said light sensitive cell in the absence of a sheet of material to cut off the fluid pressure at the distributing system, whereby the sheet of material is gravitationally stacked on the stack receiving means.
